UNITED STATES PATENT OFFICE.

RUFUS H. NULL, OF GREENSBORO, NORTH CAROLINA.

ADJUSTABLE TABLE-LEG CLAMP.

1,273,088.

Specification of Letters Patent. Patented July 16, 1918.

Application filed August 31, 1917. Serial No. 189,142.

To all whom it may concern:

Be it known that I, RUFUS H. NULL, a citizen of the United States, residing at Greensboro, in the county of Guilford, State of North Carolina, have invented a new and useful Adjustable Table-Leg Clamp; and I do hereby declare the following to be a full, clear, and exact description of the invention, such as will enable others skilled in the art to which it appertains to make and use the same.

The present invention relates to an improved fastening means for furniture legs, and has for its object to provide a device of this character whereby the leg of a table or like article of furniture can be securely clamped in position in such a manner that it can be readily released at any time, or any looseness therein quickly taken up. Further objects of the invention are to provide an adjustable furniture leg clamp which is comparatively simple and inexpensive in its construction, which can be utilized in the manufacture of tables and like articles of furniture, since it eliminates the necessity of weakening the table leg by boring a hole through the same to receive a bolt, and which will enable any looseness to be easily and quickly taken up at any time. With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawing, in which:

Figure 1 is a top plan view of a table leg fastening constructed in accordance with the invention, the table top being removed and portions being broken away and shown in section to illustrate more clearly the details of construction.

Fig. 2 is a side elevation of the table leg fastening means, the lower end of the table leg being broken away and the table top appearing in section.

Fig. 3 is a detached perspective view of one of the L-shaped clamping members.

Corresponding and like parts are referred

to in the following description and indicated in all the views of the drawings by the same reference characters.

55

For the purpose of illustration the invention is shown as applied to the leg of a table, although it will be understood that substantially the same construction can be utilized for clamping in position the leg of any similar article of furniture. The numeral 1 designates the top of a table, and 2 the usual side flange or apron which is pendent from the periphery of the table top. The table leg 3 terminates at the upper end thereof in a shank 3^a which has one side thereof cut-away to provide a flat face 4 adapted to fit squarely against the inner side of the depending flange 2 of the table top. A shoulder 5 at the lower end of the flat face 4 of the shank 3^a abuts against the lower edge of the flange 2, while the outer side of the said shank has the corners thereof beveled, as indicated at 6.

65

A pair of similar and complementary positioning blocks 7 are applied to the inner face of the depending flange 2 on opposite sides of the table leg, being rigidly secured in position by suitable fastening members such as the screws 8, and being preferably slightly spaced from the table leg so as to provide a small clearance space between the members. Fastening members 9 may also be provided for securing the positioning blocks 7 to the table top 1. Fitted against the outer faces of the positioning blocks 7 are L-shaped clamping members 10, the short arms of the said L-shaped members extending inwardly at the inner corners of the positioning blocks 7 and terminating in wedge shaped noses 11 which engage the beveled corners 6 of the table leg shank. The long arms 10^a of the L-shaped clamping members have a wedge shaped formation and gradually increase in thickness from their intersection with the short arms to the free ends thereof. These long arms 10^a of the clamping members are secured to the positioning blocks 7 by means of bolts 12 which pass loosely through openings 13 therein, and are provided at their outer ends with polygonal heads 12^a. The openings 13 are sufficiently large to allow for the necessary lateral play of the clamping bolts 12 therein, and the

100

- 5 polygonal heads 12^a of the bolts project from the clamping members in such a manner that they can be readily engaged by a wrench or other tool for tightening or loosening the same. The outer faces of the long arms and short arms of the L-shaped clamping members are shown as disposed in substantially right angles to each other, while the inner faces of the said arms are arranged 10 at an acute angle. When the clamping members are fitted against the outer faces of the positioning blocks 7 in operative position, the inner sides of the long arms of the clamping members are inclined inwardly 15 away from the faces of the positioning blocks with the outer ends of the wedge shaped long arms 10^a bearing against the positioning blocks, while the wedge shaped noses 11 of the short arms bear against the 20 beveled corners 6 of the table leg shank 3. This is clearly indicated by Fig. 1, and it will be obvious that with this arrangement the table leg can be rigidly clamped in position by tightening the clamping bolts 12, 25 and that any looseness which may subsequently develop can be easily taken up by the further tightening of the said clamping bolts. On the other hand, should it be desired to remove the table leg for any purpose, it is merely necessary to loosen the 30 clamping bolts 12 and release the L-shaped clamping members 10 from their engagement with the beveled corners 6 of the shank of the table leg. This provides a simple 35 construction which enables the table leg to be firmly held in operative position without the necessity of weakening it by boring a hole therein to receive a bolt or similar fastening member.
- 40 Having thus described the invention, what I claim as new and desire to secure by Letters Patent, is:—
1. The combination with an article of furniture including a vertical side flange 45 and a supporting leg having a shank at the upper end thereof which is formed with a flat face fitting squarely against the before mentioned side flange and with beveled outer corners, of spaced positioning blocks secured 50 to the flange on opposite sides of the shank, and clamping members adjustably secured to the positioning blocks and formed with wedge shaped portions engaging the beveled corners of the table leg shank to clamp it 55 tightly in position.
  2. The combination with an article of furniture including a vertical side flange and a supporting leg having a shank at the upper end thereof which is formed with a flat face fitting squarely against the said side flange and with beveled outer corners, of 60 spaced positioning blocks secured to the flange on opposite sides of the table leg shank, and L-shaped clamping members each having one arm thereof secured to the corresponding positioning block while the other arm thereof terminates in a wedge shaped nose engaging one of the beveled corners of the table leg shank. 65
  3. The combination with an article of 70 furniture formed with a vertical side flange, and a supporting leg having a shank at the upper end thereof which is formed with a flat face fitting squarely against the said side flange and also with beveled outer 75 corners, of spaced positioning blocks secured to the said flange on opposite sides of the furniture leg shank, L-shaped clamping members applied to the outer faces of the positioning blocks, one arm of each of the 80 L-shaped clamping members terminating in a wedge shaped nose which engages one of the beveled corners of the furniture leg shank, while the opposite arm thereof has a wedge shaped formation and extends across 85 the outer face of the corresponding positioning block, and clamping bolts extending loosely through the last mentioned arms of the L-shaped clamping members and adjustably securing them to the positioning blocks. 90
  4. The combination with an article of 95 furniture formed with a vertical side flange, and a supporting leg having a shank at the upper end thereof which is formed with a flat face fitting squarely against the said side 100 of the flange and with beveled outer corners, of spaced positioning blocks secured to the flange on opposite sides of the shank, a pair of L-shaped clamping members, the short arm of each clamping member terminating in a wedge shaped nose which engages a beveled corner of the supporting leg shank, while the long arm of each of the 105 clamping members has a wedge shaped formation and gradually increases in thickness from its intersections with the short arm 110 to the free end thereof, said long arms of the clamping members having openings therein and the thickened free ends thereof having a rocking engagement with the outer faces of the positioning blocks, and clamping bolts extending through the openings of the long arms of the clamping members and engaging the positioning blocks. 115
  5. The combination with an article of 120 furniture formed with a vertical side flange, and a supporting leg having a shank at the upper end thereof which fits against the side flange and is provided at its outer side with a beveled corner, of spaced positioning 125 blocks secured to the flange on opposite sides of the supporting leg shank, and an L-shaped clamping member, one arm of the clamping member terminating in a wedge shaped nose which engages the beveled corner of the supporting leg shank, while

the opposite arm of the L-shaped clamping member is formed with an opening and has a rocking engagement at its outer end with the face of one of the positioning blocks, 5 and a clamping bolt passing through the said opening and engaging the positioning block.

In testimony whereof I have signed my

name to this specification in the presence of two subscribing witnesses.
